UNITED STATES PATENT OFFICE.

CHARLES HENRY DOUGLAS, OF CHICAGO, ILLINOIS.

EMERY-WHEEL DRESSER.

SPECIFICATION forming part of Letters Patent No. 389,064, dated September 4, 1883.

Application filed December 27, 1886. Serial No. 922,741. (No model.)

To all whom it may concern:

Be it known that I, CHARLES HENRY DOUGLAS, a citizen of the United States, residing at Chicago, in the county of Cook and State of Illinois, have invented a new and useful Emery-Wheel Dresser, of which the following is a specification.

My invention relates to improvements in emery-wheel dressers in which wheels or disks are employed to revolve idly against the surface of the wheel to be dressed; and the objects of my improvements are, first, to cause the said disks to revolve more freely and with more firmness and accuracy than the devices heretofore employed for that purpose; second, to effectually exclude emery and dust from the bearings and to provide for their more perfect lubrication; third, to provide an easy and convenient means of taking up any rattle or lost motion caused by wear or otherwise in the bearings of the disk-shaft; fourth, to provide a means of guiding the dressing-disks in a straight line in front of the wheel to be dressed, and at the same time to afford a convenient method of adjusting them against the wheel as it becomes dressed away. I attain these objects by the mechanism illustrated in the accompanying drawings, in which—

Figure 1 is a top view of a hand emery-wheel dresser; Fig. 2, a side view of the large or disk end of the same, enlarged. Fig. 3 is a transverse section of Fig. 2 on a line through the center of the disks and shaft. Fig. 4 is an elevation of an emery-wheel dresser mounted on ways. Fig. 5 is a top view of the same. Fig. 6 is a transverse section of Fig. 2 with the male centers upon the disk-shaft.

Similar letters refer to similar parts throughout the several views.

The disks B are attached firmly to the shaft a, which is suspended and allowed to revolve upon the conical centers d and e. In the center of shaft a there is a passage-way, g, for holding and conveying oil to the bearings, and also a passage, f, in the conical center e, through which the oil is supplied. When this shaft is in motion, the oil in the passages gradually oozes out around the bearings, lubricating them, and also forcing away the emery and dust that may have settled upon the centers. The oil is held in the opening f by a metal cap, i, that slides over the opening.

A is the stock of the hand emery-wheel dresser, which is made in two parts and held together with the screws b and c. By setting up screw b the center points, d and e, attached to the two halves of the stock A, are pressed into the centers of shaft a to make a close running fit, and by this device the dressing-disks B are made to revolve firmly and accurately when brought in contact with the revolving wheel to be dressed, thus making a true and even face thereon. By backing out the screws b and c the stock A will separate and allow the shaft a, with disks attached, to be removed or replaced at will. A fine adjustment can thus be made and any unnecessary play from wear or otherwise easily taken up. The disk-shaft a in Fig. 6 is provided with male centers, which revolve in the boxes h h, through which there are oil-passages f f. This form of shaft is also adjusted to a close running fit by the same device as Figs. 1, 2, and 3.

C, Figs. 4 and 5, is a bed, to which is attached a smooth round rod, E, upon which the stock D is made to slide.

F is a set-screw, the lower end of which rests upon the smooth bevel of the bed C, upon which it slides when the stock D is moved along on the rod E in the act of truing a wheel. This set-screw is used to adjust the disks B against the wheel to be trued, which it does by raising or lowering the end of the stock D, through which it screws, and causing it to tilt upon the guiding-rod E sufficiently to press the disks against the emery-wheel.

The center point d in Fig. 5 is made to screw through one of the wings of stock D for the purpose of taking out and putting in the disk-shaft; also for the purpose of adjusting it to a close running fit. This is held in place by a jam-nut or set-screw.

To use this form of dresser most effectually, the bed C is bolted or clamped to the stand with the disks B touching the emery-wheel. Then by turning the set-screw F, so as to cause the disks to press against the revolving wheel, and by sliding the stock D back and forth upon the rod E, the face of the wheel becomes nicely trued in the exact line that the shaft E may be set.

The stock A may be made in one piece of metal, with a slot in it of the proper proportions to allow the end that holds the disks to

open far enough to take out or replace the disk-shaft when required and to make the necessary adjustments.

I disclaim the patents to Bush, No. 318,952; 5 to Roberts, No. 242,046, and to Forbis, No. 367,287, as they do not embrace any part of my invention.

What I claim as my invention, and desire to secure by Letters Patent, is—

1. An emery-wheel dresser in which the disk-shaft *a* revolves on conical bearings, through which there are oil-passages *ff*, substantially as specified.

2. An emery-wheel dresser in which the 15 disk-shaft *a* is provided with a chamber or passage-way, *g*, for holding and conveying oil to lubricate the bearings of the same, as specified.

3. The combination, in an emery-wheel dresser, of the conical centers and bearings of 20 the disk-shaft *a*, and the oil-passages *f* and *g*, for lubricating the same, as specified.

4. An emery-wheel dresser in which the conical bearings *d* are made adjustable in the wing of the stock *D*, for the purposes herein 25 specified.

5. An emery-wheel dresser in which the two sides of the stock *A* at the end which holds the dressing-wheel are drawn toward each other and secured together by the screw *b*, 30 which extends into both sides of the stock *A* for that purpose, as specified.

6. An emery-wheel dresser provided with a bed, *C*, and a rod, *E*, or its equivalent, upon which the stock *D* may be slid or moved from 35 one end toward the other, as on ways, for the purpose of dressing a true face or angle upon the emery-wheel, as specified.

CHARLES HENRY DOUGLAS.
